UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS.

ORE-CAR.

1,133,614.

Specification of Letters Patent.

Patented Mar. 30, 1915.

Application filed July 25, 1914. Serial No. 852,999.

To all whom it may concern:

Be it known that I, ARGYLE CAMPBELL, a citizen of the United States, residing at Chicago, in the county of Cook and State 5 of Illinois, have invented a certain new and useful Improvement in Ore-Cars, of which the following is a full, clear, concise, and exact description, reference being had to the accompanying drawings, forming a part 10 of this specification.

This invention relates to improvements in ore cars.

One object of the invention is to provide an ore car which is adapted to be used with 15 a number of similar ore cars in a train to dump the ore into the pockets of the ore docks, each car being so designed that it is adapted to dump the ore into two adjacent ore dump pockets and in a train of cars on 20 the dock, two pockets out of every three will be dumped into.

Another object of the invention is to provide a car of the above indicated type having a larger capacity than those heretofore 25 generally used in such service, the increased capacity being obtained by mounting the doors in a manner hereinafter specified.

A further object of the invention is to provide operating mechanism for the doors 30 so arranged that it can be operated with equal facility from either side of the car.

The invention furthermore consists in the 35 improvements in the parts and devices and in the novel combination of the parts and devices herein shown, described or claimed.

In the drawing forming a part of this specification, Figure 1 is a part central vertical section and part side elevation of a car embodying my improvements, the left hand 40 end of the car as viewed in Fig. 1 being in section and the right hand end in elevation. This figure also illustrates the relation of the car length to the spacing between the ore dock pockets and the relative location 45 of the hoppers in the car. Fig. 2 is a top plain view of one-half of the car, parts being broken away to more clearly illustrate the construction. Fig. 3 is a vertical sectional view of the car, the left hand half of 50 the figure being a section at the center of the car on line A A of Fig. 1 and the right

hand half being a section on the line B B of Fig. 1. Fig. 4 is a vertical transverse sectional view taken substantially on the line C C of Fig. 1, one of the hopper doors being shown in closed position and the other in open position. Fig. 5 is a detail view showing the arrangement of one of the latch and ratchet devices employed in the door operating mechanism and Fig. 6 is a similar 60 view illustrating part of the door operating mechanism, particularly the winding drum and links connected to the door.

In the ore carrying service, it is a common practice to ship the ore in cars and to 65 run the train of cars on to an ore dock which is provided with a plurality of pockets which are 12 ft. from center to center. Hitherto, 24 ft. cars have been generally used in this service with the result that the 70 ore could only be dumped into alternate pockets of the dock, it being understood that the ends of the car and the couplers and draft gear require an amount of space which corresponds to approximately half the length 75 of a pocket. These portions of the cars may be termed "non-productive" inasmuch as they cannot be utilized for the carrying of the ore. With my invention, I provide a car which is approximately 36 ft. long from 80 center to center of the couplers and the same is arranged with two hoppers equally spaced from the longitudinal center of the car so that each hopper is adapted to dump into a pocket. With a car of this construction, the 85 operating company derives a bigger advantage due to the fact that a decreased number of cars have to be operated; an increased percentage of the ore or other material is hauled relative to the non-productive 90 load of the car body; and the spacing of the two hoppers of my improved car is such that when it is employed in a train having cars of length of a lesser multiple of the distance from center to center of the receptacles or pockets into which the load is to be 95 dumped and which are capable of dumping into alternate receptacles only, the load may be dumped from the two hoppers of my improved car into two adjacent receptacles 100 without interference.

In the drawing, the car body is designated

generally by the reference D and, as shown in Fig. 1, its length from center to center of the couplers is approximately 36 ft. The sleepers of the ore dock are designated by the reference 10, and as shown, the same are substantially 2 ft. square and are spaced apart, center to center, approximately 12 ft. which is the standard practice. The car D, as shown, is provided with side sills 11—11 which are in the form of channels, there being two channels on each side of the car oppositely faced and united by a top plate 12. Vertical end sheets 13 are provided at each end of the car. As clearly shown in Fig. 1, the car may be considered as constituted of two like halves one on each side of the longitudinal center, and inasmuch as each part or half is the same, I shall only describe one of them.

Each half of the car is provided with a hopper or pocket E which is formed by side walls 14—14 inclined at their lower end as indicated at 15; an inclined inner end wall 16 and an inclined outer end wall 17, the end walls 16 and 17 being extended to a point below the side sills as clearly indicated in Fig. 4. All the walls forming the hoppers are suitably braced, the side walls by the side stakes 37 and inclined diagonal braces 38—38. The opening at the bottom of each hopper is closed by two doors 18 each of which is hinged at its outer edge by means of hinge brackets 19 pivotally connected to hinge butts 20 secured on the outer side of the inner channel 11 forming the side sill. Each door 18 is provided with a depending flange 21 which extends around the end and inner edges thereof, see Fig. 4. Bracing irons 22 and 23 are also secured to the under side of each door to properly strengthen the same. By referring to Fig. 4, it will be seen that the doors 18, when in closed position, incline inwardly and downwardly and at their outer portions are raised above the lower edge of the end walls 17 so that the closure at the ends of the pockets is effected by the edges of the end sheets 16 and 17 and the end portions of the depending flanges 21 of the door. In this way, I am enabled to obtain an increased capacity due to the fact that the end walls 17 may be placed nearer the ends of the cars than they otherwise could be, it being borne in mind that certain factors must always be taken into consideration in designing the cars such, for instance, as the inclination of the end sheets, the door opening area and the clearance which must be maintained between the doors and the trucks when the doors are open. Each iron 22, at its ends is provided with laterally extended projections 24 to which projections are secured the bolts 25 forming the end link of each winding chain 26, the other end of each chain being pivotally secured to the drum 27 fixed to a transversely extending shaft 28. As clearly shown in Fig. 2, the winding chains and drums are arranged in pairs at each end of the doors so that rotation of the shafts 28 operates both doors for each pocket simultaneously. The shafts 28 which extend from side to side of the car, are each provided with a bevel gear 29, the bevel gears 29—29 coöperating with bevel gears 30 secured to the ends of a longitudinally extending shaft 31 which is mounted in suitable bearings in the side of the car above the side sills whereby the shafts 28—28 are operated simultaneously. The shaft 28 which is located nearest the center of the car has secured thereto at its ends, ratchet wheels 32. Coöperating with each ratchet wheel 32, on each side of the car, is a pawl or dog 33 and a latch 34, the dogs 33 being secured to the opposite ends of a transversely extending shaft 35 and the latches 34 being secured to the ends of a transversely extending shaft 36. With this arrangement, it is apparent that the dogs and latches for each door operating mechanism may be operated from either side of the car, which is an important consideration, particularly in the ore carrying service where the operators are obliged to work on relatively narrow docks.

I have herein shown and described in detail, one embodiment of my improvement but the same is merely illustrative as I am aware that the invention may be embodied in other structures without departing from the spirit of the invention and I contemplate all changes and modifications as come within the scope of the claims appended hereto.

I claim:

1. An ore car having the total length thereof from coupler center to coupler center a multiple of the distance from the center to center of receptacles into which it is arranged to dump the load, said car being divided at the center longitudinally thereof, into hoppers, the center of each of said hoppers being approximately equidistant from the transverse center line of the car, the spacing of said hoppers permitting the dumping of the load into two adjacent receptacles of a uniformly spaced series, without interference when in a train having included therein cars of a length of a lesser multiple of the distance from center to center of said receptacles and capable of dumping into alternate receptacles only.
2. An ore car of the character described having a plurality of longitudinally arranged hoppers intermediate the trucks, the hoppers having inclined end walls and bottom doors, the distance, longitudinally of the car, between the centers of said hoppers, substantially approximating the distance from the center of the coupler at one end of

the car to the center of the hopper nearest thereto, the said spacing of said hoppers permitting the load of the car to be dumped into two adjacent receptacles of a uniformly spaced series, without interference when in a train having cars of a lesser length from center to center of couplers and capable of

dumping into alternate uniformly spaced receptacles only.
